UNITED STATES PATENT OFFICE

2,418,715

REFRIGERATED SODA FOUNTAIN CABINET

Herman K. Johnson, Grand Haven, Mich., assignor to The Bastian Blessing Company, Chicago, Ill., a corporation of Illinois

Application February 25, 1942, Serial No. 432,311

12 Claims. (Cl. 62—7)

1

This invention relates to refrigerating apparatus, and more particularly to that type having a plurality of chambers maintained at different temperatures.

One of the objects of the invention is the provision of a new and improved hermetically sealed unit with a plurality of expansion coils so constructed and arranged that the temperatures of the compartments containing the coils are different and will remain substantially constant between predetermined limits.

Another object of the invention is the provision of a multi-compartment refrigeration apparatus provided with refrigerating mechanism comprising an expansion coil for each compartment, with the coils having different temperatures and all arranged in series for preventing short cycling of the apparatus.

A further object of the invention is the provision of a new and improved hermetically sealed refrigerating unit of the dry type or system that may be assembled as a complete unitary automatically controlled structure normally requiring no attention during its use or during the life of the machine.

A still further object of the invention is the provision of a multi-compartment refrigeration apparatus having new and improved means so constructed and arranged that the compartments may be automatically maintained at different temperatures without the aid of either expansion or differential pressure valves.

Another object of the invention is the provision of a self-contained refrigerating unit or fountain cabinet, and installed apparatus, that is comparatively inexpensive to manufacture, easily assembled, efficient in operation, automatically controlled, and that is extremely simple in its operating and control mechanism.

Other and further objects and advantages of the invention will appear from the following description, taken in connection with the accompanying drawings, in which

Fig. 1 is a perspective view of a soda fountain cabinet;

Fig. 2 is a diagrammatic showing of the refrigerating mechanism employed in the fountain; and

Fig. 3 is a section of one of the restricted portions of the refrigerating system, with parts broken away.

In the manufacture and use of refrigerating units especially adapted for counter fountains, and the like, it is common practice to so construct and mount the separate expansion coils for the

2

different compartments that the separate compartments may be maintained at different temperatures. In such an arrangement the expansion coils for the different compartments are usually in parallel, thus necessitating the use of both differential pressure and expansion valves. It has also been considered necessary to employ a comparatively large charge of refrigerant.

The controls of the conventional type of refrigerating units are complicated. As a rule a construction maintaining a multi-compartment unit at different temperatures for the compartments requires the use of motors of greater than one-half horse power for operating the system. But it is considered to be good practice, where the motor required is greater than one-half horse power, to employ an electric starting device for starting the motor, which, of course, complicates the structure and adds to the initial cost of the system, and is more or less expensive to operate beside occupying additional space.

The present invention seeks to greatly reduce the original cost of the apparatus and its cost of installation, as well as materially reducing the running expenses of the entire refrigerating apparatus.

During the present crisis the material employed in the manufacture of refrigerating devices is of vital importance. The present system requires a minimum of material since numerous parts, as valves and the like, have been eliminated and other parts greatly simplified. The amount of refrigerant is greatly reduced. In a refrigerating apparatus formerly requiring 10 to 12 pounds of Freon (F-12), with a half horse power motor for operating the refrigerating mechanism, an apparatus of the same capacity requires only 3 to 4 pounds of the same refrigerant, and the device may be operated by a third horse power motor.

Furthermore, in maintaining the separate compartments of a dry system refrigerating apparatus at different temperatures, it is common practice to provide a surge tank into which the refrigerant from higher temperature compartments may expand in order to prevent short cycling of the system. But in the present system, where the expansion coils are all in series, the surge tank is eliminated and the charge is greatly reduced. Both of these features are considered of great importance, and especially when taken in connection with the fact that a smaller motor may be employed and that no valves and but one control is required.

The apparatus which includes the cabinet and

refrigerating mechanism are assembled as a unit at the factory, the compressor and motor are assembled as a single hermetically sealed unit, as shown diagrammatically at 60 in Fig. 2, and all joints between the coils and connecting conduits are also hermetically sealed, as by brazing, so that the complete apparatus may be manufactured and sold as an hermetically sealed apparatus at a greatly reduced price. This is considered a very important feature of the invention, because it not only conserves material but the assembled unit may be sold at a greatly reduced price.

Referring now to the drawings, the reference character 10 designates a fountain or refrigerating cabinet having a plurality of compartments. The cabinet has front and back side walls 11, end walls 12, and a top wall 13. The cabinet is divided into a plurality of chambers or compartments comprising what, for convenience of description, will be termed a condensing chamber or compartment 14; a storage chamber or compartment 15; a liquid or water bath compartment 16; ice cream compartment 17; and a hardening compartment 18.

The front portion of the cabinet has an upward projection 19, in the form of a compartment extending the full length of the cabinet, and which will be referred to as the jar rail. This jar rail is provided with a top wall 21, on which is mounted the fountain or dispensing arms 48, 49, for the sweet water and for the carbonated water. Contiguous to the top wall 21, and extending downwardly and rearwardly therefrom, is a jar supporting plate 23, within which is mounted the containers for the removal jars 24 containing the various flavored syrups, as is usual in such constructions. A depression 25 is provided beneath the fountain or dispensing valves 22 for providing a seat or support for the glasses or other containers used in serving the public from the dispensing arms.

The compartments 15, 17 and 18 are provided with hinged closures 26, 27 and 28, and the compartment 16 is provided with a removable closure 29. Since the construction of the fountain or cabinet is substantially like those of the conventional type, it is not thought necessary to describe the same more in detail except to state that each one of the compartments, except the compartment 14, is provided with a conventional insulating material on the walls of the compartment. The compartment 16 is filled with water 31, as indicated in Fig. 2 of the drawing, which functions as a heat exchanger fluid, as will presently appear.

The refrigerating mechanism is so constructed that there will be an evaporating or cooling member for each compartment, which, in the present instance, is in the form of coils. Any suitable refrigerant expansion members may be employed, but for illustrating one embodiment of the invention these expansion members will be described as being in the form of coils or pipes of the usual construction, and of the conventional heat conducting material usually employed in refrigerating apparatus of this type.

The refrigerating system is of the compression type. The condensing unit is shown diagrammatically at 40 in Fig. 2, and comprises a hermetically sealed compressor 32 and a condenser 34. The compressor is operated by a motor 33, the armature 50 of which is indicated in Fig. 2. The compressor is of the multiple cylinder type, only one cylinder being shown in the diagram. These cyl-

inders are located in the air stream of the condenser fan, which tends to cool them. The pistons are operated by a crank on the vertical armature shaft, as indicated in Fig. 2. The compressed refrigerant passes from the compressor 32 through the condenser 34, which is air cooled by a suitable fan 35. The condenser or condenser coil 34 is housed in a casing 350 surrounding the fan and condenser. The condenser coil 34 may, if desired, be water cooled, but it is shown as being air cooled in the present construction, so that the unit may be more easily installed.

From the condenser 34 the refrigerant passes along through the main lead, pipe or pressure conduit 30, then through a restrictor section 36 of the refrigerant line 30. This restrictor section is of comparatively short length, and very materially less in internal diameter than the pipe 30, so that it functions as an expansion valve. The refrigerant is expanded into an expansion coil 37, which may be, and preferably is, of larger diameter than that portion of the pipe 30 between the condenser 34 and restrictor section 36. The coil 37 is located in the storage chamber 15 for cooling the latter. It is arranged around the compartment 15 in the usual manner, for cooling the compartment. From the chamber 15 the refrigerant is discharged into the water bath chamber 16, into the coil 38, which is in series with the coil 37 and may be of substantially the same diameter.

The further expansion of the refrigerant in the coil 38 will cool the water 31 in the chamber 16, and this water in turn will cool the sweet water and the carbonated water, which are led into the chamber through the tubes 39 and 41, from suitable sources of supply. These tubes are in communication with corresponding coils 42, 43, which are immersed in the water 31 in the compartment 16. The coils 42 and 43 extend above the cabinet, as shown at 44, 45, respectively, and are connected to the valves 22, 22. These valves are carried by the arms 48, 49, and control the passage of the sweet water and the carbonated water through the chamber 16, where they have their temperatures reduced.

From the compartment 16 the refrigerant passes through a second restrictor section 51, which is in series with the passage 30, 38. The diameter of this tube is considerably smaller than the main line 30, so that this restrictor section 51 also functions as an expansion valve. The refrigerant passing through this restrictor tube expands into a coil 52 in the counter rail compartment 19 for maintaining the jars 24 at the desired temperature. The diameter of the coil 52 may be, but not necessarily so, of slightly less diameter than the coil 38. From the compartment 19 the refrigerant passes into a section line 30^a, which is an extension of the main line 30, and into the ice cream compartment through the expansion coil 53 therein.

The main line extension and expansion coil 53 have substantially the same diameters, and preferably, though not necessarily, have a diameter greater than the main line 30 or coil 38. This gives a greater expansion space per foot length of pipe, so that, being nearer the suction end of the main extension line 30^a, the temperature in the chamber or compartment 17 may be materially reduced over the temperatures in any of the foregoing compartments. From the coil 53 the refrigerant passes over into the hardening compartment 18 through the pipe 30^a, then through the expansion coil 54 for maintaining

this compartment at a temperature materially lower than the freezing point of water, and below the temperature in any of the other compartments. From the coil 54 the refrigerant passes through the suction line 30^a back to the compressor, thus completing the cycle of operation.

The condenser coil 34, the expansion coils 37, 38, 52, 53 and 54 are all in series with the compressor, and with the restrictor sections 36 and 51. The lengths and diameters of the various coils, and the restrictor tubes or sections, will vary with the different sizes of installations, with the efficiency of the heat insulating material employed for the cabinet, with the room temperature, with the number of compartments employed, with the differences of temperatures maintained in these compartments, and with the amount of refrigeration required, as well as the type of compressor employed and the kind of refrigerant used, and various other factors too numerous to mention.

Suitable means are provided for controlling the operation of the compressor motor 33. As shown, this is accomplished by a conventional thermostatically controlled switch 55, which is adapted to be operated by a volatile fluid in a fluid expansion bulb 56, located in one of the compartments, as is well known in the art. As shown, it is located in the hardening compartment 18, Fig. 2. The thermostat-controlled switch may be of any or the usual or well known type, such, for instance, as the lever toggle type operated by a bellows that is opposed by a spring, the compression of which is adjustable by the member 57 for adjusting the operation of the control 55 for varying the temperatures in the compartments. By adjusting the set-screw or adjusting member 57 to change the spring compression, it changes the pressure required for operating the switch, and consequently varies the cycling period of the apparatus.

Since the specific details of this control constitute no part of the present invention, it is not thought necessary to illustrate or describe the same in detail. Any one of the various thermostat type controls, preferably the snap type for preventing arcing, may be employed for this purpose.

When the temperature in the chamber 18 rises above a predetermined amount the pressure developed by the expansion of the expanding fluid in the bulb 56 will become sufficient to operate the switch 55, and this will in turn close the circuit through the motor 33. Likewise the lowering of the temperature within the hardening compartment, as a result of the operation of the compressor, will cause a contraction of the fluid in the bulb 56, thus permitting the spring in the thermostatic control to open the switch 55 and stop the motor, as is well understood in the art. Since the motor is not greater than one-half horse power, it is not necessary to provide a relay starting mechanism for the motor, but the same is started directly by closing the switch 55.

In the construction shown all of the joints connecting the main line 30 and 30^a to the various expansion coils and restrictor sections are brazed, and are all installed in the cabinet, so that the entire apparatus constitutes a unitary hermetically sealed structure that may be sold as a single unit, thereby greatly reducing the cost of equipment and installation.

Since the various coils may be varied in both

length and diameter, as well as the kind of material employed, it is not possible to give a definite set of dimensions that will fit all conditions. For instance, the volume capacity of a given expansion coil may be increased by lengthening the coil, or by increasing its diameter. Shorter coils of larger diameter require less space to house, for the same volume capacity, than coils of greater length. On the other hand, coils of smaller diameter have a relatively greater heat conducting surface than larger coils.

The following dimensions for a nine foot, forty gallon fountainette, having the compartments described above, and employing a charge of three pounds of Freon (F-12) as the refrigerant, was found to operate satisfactorily, and is given as one example. A third or half horse power motor was employed or operating the compressor, the main line 30 up to the restrictor section 36 from the condenser 34 is $\frac{1}{4}$ " outside diameter and about 7' long, the suction or extension 30^a from the coil 54 to the compressor is 8 feet long and is $\frac{5}{8}$ " outside diameter; the restrictor passage 36 is .037" inside diameter, 36" long; the tube of the coils 37 and 38 are a half inch outside diameter, and together are about 55' long, and are about the same length; the restrictor tube 51 is .070" inside diameter and about 24" long; the tube of the coil 52 is $\frac{3}{8}$ " outside diameter and about 18' long; and the tubes of the expansion coils 53 and 54 are $\frac{5}{8}$ " outside diameter and together are about 87' long, and are substantially of the same length. The temperature of the room within which the cabinet was placed was about 86°.

The jar rail was maintained at an average temperature of 41° F.; liquid in the syrup jars was maintained at 46°; the storage compartment at around 32°; ice cream compartment at around 3° above zero, and the hardening compartment at about -5°. The average operating time was approximately 65%. These dimensions are given by way of example only. It is understood that these measurements may be varied within certain limits, even for the same capacity fountain.

It will thus be seen that the refrigerant is circulated in series through the various compartments, and that no expansion or pressure controlled valves are necessary. It will also be appreciated that the motor and compressor unit is hermetically sealed, and that the system is the hermetic type, and, as a result, the apparatus may be readily installed, and that it will only be necessary, in installing the device, to make the proper connection with the sweet water supply pipe and the carbonated water supply pipe when the apparatus is purchased as a complete unitary structure.

If desired, suitable means may be provided whereby the compressor and condenser may be removed from the system for repairs or replacement. While the condenser is shown exterior of the power unit, it is understood that this is the preferred form only, and that the condensing unit may be located within the compressor housing and in the base of the machine in event the condenser is water cooled.

It is thought from the foregoing, taken in connection with the accompanying drawings, that the construction and operation of my device will be apparent to those skilled in the art, and that changes in size, shape, proportion and details of construction may be made without departing from the scope and spirit of the appended claims.

I claim as my invention:

1. In a refrigerating apparatus, a hermetically sealed refrigerating unit comprising a plurality of evaporating containers, conduit means connecting said containers, means for circulating a volatile refrigerant in a closed circuit through said containers and said conduit means in series, a plurality of restrictions within said conduits each having a permanently open passage therethrough and functioning as expansion valves for maintaining said evaporating containers at different temperatures, a separate cooling compartment for each evaporating container, a thermo-sensitive device within one of said compartments for controlling the operation of said second-named means, one of said compartments having a pair of coils for carbonated and sweet water extending therethrough and a heat exchange liquid surrounding said coils and in contact with the evaporating container within said one compartment for constituting a heat exchange medium, said evaporating containers constituting the sole metallic heat exchange elements within said apparatus.

2. In a refrigerating apparatus, a cabinet having a chamber for housing the operating mechanism, a storage compartment, a liquid bath compartment, a jar rail compartment, an ice cream compartment and a hardening compartment, a compressor and condenser within said chamber, coils for sweet and carbonated water, expansion coil extending through said liquid bath compartment, a liquid within said last-named compartment constituting a heat exchange medium, an expansion coil in each of the remaining compartments, conduits connecting said compressor, condenser and expansion coils in series in a closed circuit through said compartments in the order first named, a restriction in said circuit anterior to the expansion coil within said storage compartment, a restriction in said circuit between the expansion coils in said liquid bath compartment and jar rail compartment, said compressor and restrictions constituting the only obstruction aside from friction to the free flow of refrigerant through said circuit, thermo-sensitive means controlled by the temperature within said hardening compartment for controlling the circulation of said refrigerant through said circuit, and means for adjusting said last-named means.

3. In a refrigerating system, a plurality of compartments, a compressor, a condenser, a conduit extending from the discharge of said compressor back to the suction intake of said compressor in series in a single circuit through all of said compartments, said conduit being formed into expansion coils in said compartments, a refrigerant fluid within the conduit, a pair of conduits within one of said compartments for conducting water and carbonated water therethrough, a liquid bath for the expansion coil in said last-named compartment, a restriction within said circuit immediately anterior to said last-named compartment, a restriction within said conduit immediately posterior in the direction of flow of the refrigerant to the expansion coil in said water bath compartment, and means controlled by the temperature within another of said compartments for controlling the circulation of the refrigerant through said circuit, said restrictions each comprising a length of pipe having a permanently open passage therethrough and of materially reduced cross-sectional area over that of said expansion coils and functioning as an expansion valve.

4. In a refrigerating apparatus, a plurality of cooling compartments, an expansion coil in each compartment, compressor and condenser mechanism for supplying a refrigerant to said coils, valveless passages connecting said coils in series with said mechanism, said passages having at least two sections in which the internal diameters thereof are restricted to function as expansion valves, each restriction being anterior to at least two expansion coils in the direction of flow of the refrigerant, the lengths and internal diameters of the coils being such that the second compartment after the first restriction will be maintained at a higher temperature than the first compartment and the second compartment after the second restriction will be maintained at a lower temperature than the one preceding it in the direction of flow of the refrigerant, and thermo-sensitive means for controlling the amount of refrigerant flowing through said coils in a given time.

5. In a refrigerating apparatus having a cabinet defining a plurality of refrigerating compartments separated from each other, a refrigerating system for cooling said compartments including a refrigerant liquefying unit and a conduit defining a passage open throughout its length and connected at its ends to said unit, said conduit including a separate coil in each of said compartments and a restrictor forming part of said conduit located ahead of two of said coils, said two coils being in unrestricted communication with each other and so correlated with each other as to constitute means for refrigerating and maintaining one of said two compartments at a lower temperature than the other, and thermo sensitive means located in the compartment having the lower temperature for controlling operation of the liquefying unit.

6. In a refrigerating apparatus having a cabinet containing at least three separate cooling compartments for receiving different materials to be cooled, a refrigerating system which includes a permanently open conduit means formed into an expansion coil in each of said compartments with an unrestricted connection between two of the coils, said conduit having a plurality of fixed restricted passages, one of which is ahead of said two coils for restricting the flow of refrigerant therethrough to expand it, means for liquefying said refrigerant and for circulating said refrigerant through said passage, said system being so constructed that said coils maintain the compartments at different temperatures, and thermo sensitive means disposed in one of the compartments for controlling the operation of said liquefying means.

7. In a refrigerating apparatus having a cabinet defining separate cooling, freezing and hardening compartments, the combination of a refrigerant expansion coil in each compartment constituting heat absorbing elements for said compartments, means for liquefying refrigerant, means for connecting said coils and liquefying means in series and including a plurality of restrictors and a passage for conducting the liquefied refrigerant to said coils through said restrictors, one restrictor being located anterior to and another posterior to the first of said coils and functioning as expansion devices without varying the cross-sectional area of any part of said passage under any condition, said connecting means also including a suction passage conducting the expanded refrigerant to said liquefying means, and thermal means for automatically controlling the operation of said liquefying means

in relationship to the temperature present in one of said compartments, said apparatus being constructed for maintaining said compartments at different temperatures.

8. In a refrigerating apparatus having a cabinet provided with a plurality of separate compartments, the combination of means for liquefying refrigerant, means for cooling the contents of one of the compartments including a coil and a secondary body of liquid in which refrigeration is stored by the cooling action of said coil, a coil in each of the other compartments, means for connecting the coils in series with each other and with the liquefying means including a resistor located anterior to two of said coils in communication with each other without any restriction interposed between them, and thermo-sensitive means located in one of the compartments for controlling the operation of said liquefying means, said apparatus being constructed for maintaining the contents of said compartments at different temperatures.

9. In a refrigerating apparatus, the combination of a compressor, a refrigerating unit comprising a plurality of evaporating elements of different heat absorbing areas in unrestricted communication with each other and in series with said compressor and condenser to form a refrigerant circuit, said elements being disposed in separate refrigerating compartments and constituting the heat absorbing metallic elements in said apparatus, a restriction between said condenser and the elements functioning as a refrigerant expansion device without varying the cross-sectional area of any part of said circuit at any time, said apparatus being constructed for maintaining said compartments at different temperatures and means for automatically controlling the operation of said compressor in relationship to the temperature of the lower temperature compartment.

10. A dry system refrigerating apparatus comprising at least three separate compartments providing spaces for receiving and segregating different materials to be cooled, means for circulating a refrigerant in heat exchange relationship with said compartments in series including an evaporating element for each compartment, and means including permanently open restricted passages for controlling the flow of said refrigerant through said elements, said elements being so constructed and arranged with respect to each other as to maintain the compartments at different temperatures and constituting the sole heat exchangers for said compartments, and one of said restricted passages being followed by two elements for two compartments connected together without any interposed restricting means between them.

11. In a dry system refrigerating apparatus a plurality of separate compartments, a compressor, a condenser, a plurality of expansion coils one in each compartment constituting the sole

metallic heat exchange elements in said compartments, two of said coils being in communication with each other without any restriction interposed between them, conduits connecting said coils in series with one another and with said compressor and condenser to form a closed circuit for a refrigerant to cool said compartments, and means including a plurality of permanently open restrictions interposed in certain of said conduits one of which is ahead of said two coils for maintaining certain of said compartments at lower temperatures than the remaining compartments, said system including said compressor being hermetically sealed, said restrictions and compressor constituting the sole restriction to the free movement of said refrigerant around said circuit.

12. In a refrigerating apparatus, a cabinet containing a plurality of cooling compartments each for containing materials to be cooled, an open conduit for conveying a refrigerant in heat exchange with said compartments, said conduit being formed in part of expansion coils two of which are connected in series and in communication with each other without any restriction interposed between them, one of which coils is in each of said compartments, said coils having different heat exchange areas, a restricted passage in position ahead of said two coils for restricting the flow of refrigerant into said two coils to expand the refrigerant, means for liquefying said refrigerant and for circulating said refrigerant through said conduit to develop a differential in the pressures of the refrigerant upon opposite sides of said restricted passage, said system being so constructed and arranged that predetermined temperatures may be maintained in the several compartments, and means including a thermo-sensitive device disposed in one of said compartments for controlling operation of said liquefying means.
